UNITED STATES PATENT OFFICE.

BERTHA GALLAND, OF NEW YORK, N. Y.

GARMENT.

No. 884,479.

Specification of Letters Patent. Patented April 14, 1908.

Application filed March 23, 1907. Serial No. 364,079.

To all whom it may concern:

Be it known that I, BERTHA GALLAND, a citizen of the United States, and a resident of the city of New York, borough of Manhattan, in the county and State of New York, have invented a new and Improved Garment, of which the following is a full, clear, and exact description.

The invention relates to night-gowns, wrappers, kimonos and the like, and its object is to provide an expensive yoke, and a durable body of ordinary white goods, to permit of washing the body as often as required independent of the yoke and without subjecting the expensive yoke to the ruinous washing action, the yoke being only cleaned from time to time, thus insuring long life to the yoke and permitting its use with a number of bodies.

20 The invention consists of novel features and parts and combinations of the same, which will be more fully described herein-after and then pointed out in the claims.

Reference is to be had to the accompanying drawings forming a part of this specification, in which similar characters of reference indicate corresponding parts in all the views.

Figure 1 is a front elevation of the improvement, part of the covering flap being turned up to show the attaching device for attaching the body to the yoke; Fig. 2 is an enlarged transverse section of the same, on the line 2—2 of Fig. 1; Fig. 3 is a side elevation of a modified form of the body, and Fig. 35 4 is an enlarged transverse section of the same and the yoke to which the body is attached by lacing.

The yoke A of the garment is preferably made of lace or other expensive material, 40 while the body B is of ordinary plain white goods and is removably attached to the yoke A. For the purpose mentioned the yoke A is provided at its lower end with a depending band A', to which is removably attached the upper end of the body B by use of suitable fastening devices such, for instance, as buttons C secured to the band A' and engaging button holes B' on the upper end of the body B. A covering flap A² also depends from the lower end of the yoke A, to cover up the joint between the upper end of the body B with the band A', as plainly indicated to the left in Fig. 1. The covering flap A² is provided with a lacing band A³ adapted to be tied into a bow A⁴ at the front open end of the yoke A, to close the same, and the body

B is partly open at the front upper portion and is adapted to be closed by buttons D or other fastening devices.

The lacing band A³ on the covering flap 60 A² may be used as part of the fastening device for securing a body B³ (shown in Figs. 3 and 4) to the yoke A, the said body B³ being for this purpose provided at its upper end with openings B⁴ to be engaged by the lacing 65 band A³ instead of using the buttons C above mentioned. The body B³ referred to is also partly open at the front upper portion and is adapted to be closed by buttons D'.

Now by the arrangement described the 70 body B is detachably secured to the yoke A and its joint is completely covered by the covering flap A², as before mentioned, so that the garment looks like any other one-piece garment as now used. It will also be noticed 75 that by separating the yoke A from the body B the latter can be conveniently washed without subjecting the yoke A to the ruinous washing operation, the yoke A being cleansed from time to time in the usual manner, so that it is not injured, and consequently one single yoke readily outlasts a 80 number of bodies B, thus providing an economical garment for the user.

Having thus described my invention, I 85 claim as new and desire to secure by Letters Patent;

1. A night gown, wrapper, kimono or like garment, comprising a yoke open at the front, the yoke being provided at its lower 90 end with a flap, the said flap having a lacing band for closing the front of the yoke, a body open at the upper portion of the front and closed at the lower portion thereof, closing means for closing the upper portion of the 95 front of the body, and fastening means for removably securing the upper end of said body to the yoke, the said flap overlying the joint between the body and the yoke.

2. A night gown, wrapper, kimono or like 100 garment, comprising a yoke having a band at its lower edge, a body, fastening means for removably securing the upper end of the body to the said band, the yoke having a covering flap at its lower edge overlying the 105 said band and the upper end of the body and concealing the joint between the same, the said flap being provided with a lacing band.

3. A night gown, wrapper, kimono or like 110 garment, comprising a yoke, a body for removable attachment to the yoke, the yoke being open at the front and having a cover-

ing flap depending from the lower end thereof for covering the upper part of the body, the said flap being provided at its upper portion with a lacing band, for closing the open 5 front of the yoke.

4. A night gown, wrapper, kimono or like garment, comprising a yoke, a body detachably secured to said yoke, a covering flap depending from the lower end of the yoke 10 and overlying the joint between the body and the yoke, the said flap being provided with a lacing band.

5. A night gown, wrapper, kimono or like garment, comprising a yoke open at the 15 front, a depending band at the lower end of the yoke, a body, fastening means for re-

movably securing the upper end of the body to the said band, and a covering flap also depending from the lower end of the yoke to cover the joint between the upper end of the 20 body and the said band, the upper part of said flap being provided with spaced openings, and a lacing band engaging said openings to close the open front of the yoke.

In testimony whereof I have signed my 25 name to this specification in the presence of two subscribing witnesses.

BERTHA GALLAND.
